SASH STAY AND FASTENER

Chester O. Goserud, St. Paul, Minn.

Application October 23, 1937, Serial No. 170,672

10 Claims. (Cl. 292—263)

My invention relates to sash stays and fasteners and has for an object to provide a sash stay and fastener by means of which a swinging storm sash may be easily and readily held in adjusted position with reference to the frame in which the same is hung.

Another object of the invention resides in providing a sash stay and fastener in which the parts are so constructed as to prevent rattling of the sash.

Another object of the invention resides in providing a sash stay and fastener which may be readily and easily detached from the mounting securing the same to the sash.

Another object of the invention resides in constructing the said stay and fastener with a pair of jointed arms having a pintle issuing from one end of one of the arms and adapted to be received within a bearing in the mounting therefor and in further providing disengageable means for holding the pintle within said bearing.

A feature of the invention resides in utilizing a pivoted keeper for holding the pintle in engagement with said bearing.

Another object of the invention resides in constructing the mounting in the form of a bracket having a base and a flange, and in providing said flange with an opening having a reduced portion serving as a bearing and in further constructing the pintle with a groove adapted to be received within said reduced portion of the opening of said flange.

Another object of the invention resides in constructing the keeper with a cam adapted to engage the pintle and to force the pintle into engagement with the bearing.

A feature of the invention resides in arranging said bearing away from the base of said bracket and in arranging said keeper between the base of the bracket and pintle.

Another object of the invention resides in constructing the keeper with a groove in which the pintle is received when the keeper is in operative position.

An object of the invention resides in constructing the keeper with one or more lugs adapted to be engaged by a tool for the purpose of turning the keeper.

Other objects of the invention reside in the novel combination and arrangement of parts and in the details of construction hereinafter illustrated and/or described.

In the drawings:

Fig. 1 is a front elevational view of a portion of

a window illustrating an embodiment of my invention applied thereto.

Fig. 2 is a view similar to Fig. 1 showing the parts in altered position.

Fig. 3 is a sectional detail view taken on line 5 3—3 of Fig. 1.

Fig. 4 is a view similar to Fig. 3 showing the parts in altered position.

Fig. 5 is a view similar to Fig. 3 showing the sash fully opened.

Fig. 6 is a cross-sectional view taken on line 10 6—6 of Fig. 1.

Fig. 7 is a perspective view of one of the supporting brackets having the keeper attached thereto.

For the purpose of illustrating the application of my invention I have shown a portion of a window which is designated by the reference numeral 10. This window comprises a window frame 11 having a stop 12 extending about the same and forming a rabbet 13 in which the storm sash 14 is received. This frame also provides a groove 15 in which the regular sliding sash of the window is disposed and which forms no particular feature of the invention and has not been shown 25 in the drawings. Only a portion of the sash 14 is illustrated namely one of the stiles 16 thereof which carries a pane of glass 17 supported therein in the customary manner. The invention may also be used for screen sash and it is to be understood that where the word storm sash is used, a 30 screen sash is also intended.

In the use of the invention, preferably two sash stays and fasteners are employed, one on each side of the storm sash. These sash stays and fasteners are, however, identical in construction except that one is left handed and the other right handed and only that used on the left hand side of the window has been illustrated and will be described. This sash stay and fastener comprises 40 a pair of jointed arms 18 and 19 which are pivotally connected together at their joining ends by means of a friction joint 21. The arm 19 is pivoted to a mounting 22 secured to the stile 16 of sash 14, while the arm 18 is pivoted to a mounting 23 45 secured to the stop 12 of the window frame 11. These parts will now be described in detail.

The arm 18 is constructed from sheet metal and is stamped to provide a shank 24 having circular ears 25 and 26 at the ends thereof. The 50 ear 25 is pivoted to the mounting 23 which consists of a flat plate 27 of a width equal to the width of the stop 12. This plate is secured to the stop 12 by means of screws 28. Between the ear 25 and the plate 27 is a friction washer 29 which is 55

constructed of fibre or some other similar material. A rivet 31 passing through the ear 25, washer 29 and plate 27 and riveted over said plate serves as the pintle for connecting the arm 18 to the mounting 23.

The arm 19 is constructed similar to the arm 18 and is formed with a shank 32 and circular ears 33 and 34 at the ends thereof. Issuing outwardly from the end of the ear 26 of arm 18 is a strap 35 which terminates in another circular ear 36. The strap 35 is bent U-shaped in form, as shown in Fig. 2, so that the ear 36 overlies the ear 26. The ear 34 of arm 19 is disposed between the ears 26 and 36. Between the three ears are arranged friction washers 37 and 38. A bolt 39 having a square head 41 passes jointly through the ears 26, 34 and 36 and the washers 37 and 38. The head 41 of bolt 39 is received within a square hole in the head 26 and is held from rotation thereby. Upon the end of the bolt 39 is a nut 42 by means of which the joint may be tightened. Nut 42 engaging the ear 36 which is integral with the ear 26 is thereby prevented from rotating as the arms 18 and 19 swing relative to one another. The strap 35 is so arranged that the portion thereof, designated by the reference numeral 43, engages the edge 44 of arm 19 and limits the opening movement of said arms so that the arms cannot be arranged with dead centers. This permits 30 of closing the sash by merely drawing on the pull thereof and without prior adjustment of the arms.

The mounting 22 is constructed in the form of a bracket from sheet metal which is stamped and bent to provide a base 45 and a flange 46 extending outwardly therefrom. Base 45 is adapted to be secured to the stile 16 of storm sash 14 by means of screws 47. The flange 46 of bracket 22, as best shown in Fig. 7, is formed with an opening 48 which extends upwardly from the base 45. The uppermost portion of this opening is reduced and formed in the shape of an arcuate groove as indicated at 49, which groove provides a bearing 51. The ear 33 of arm 19 has issuing outwardly from it a pintle 52. This pintle is constructed with a spindle 53 and a head 54 at the end of the same. The other end of the spindle is constructed with a stem 55 which extends through the ear 33 and is riveted thereto. Head 52 is larger in diameter than the spindle 53 to provide a shoulder 60. The extreme end of this head is tapered as indicated at 56. The opening 48, in flange 46, is of suitable dimensions to permit of inserting the head 54 of pintle 52 through the opening. The tapered end 56 of the head 54 facilitates such insertion. The spindle 53 is of a diameter suitable to be received within the opening 49 and is guided for rotation in the bearing 51. When the parts are applied, as shown in Fig. 6, the shoulder 60 prevents axial movement of the 60 pintle 52 in one direction and thereby prevents disengagement of the spindle 53 from the bearing 51.

For holding the spindle 53 in engagement with bearing 51, a keeper is employed which is indicated in its entirety by the reference numeral 57. This keeper is constructed from sheet metal which is stamped to provide a body 58 pivoted to the base 45 of bracket 22 by means of a rivet 59. The body 58 has formed on it a head 61 which is offset from the plane of the base 45 and which is provided at its center with a groove 62. Groove 62 is adapted to receive the head 54 and forms a further bearing for the pintle 52. This bearing, in conjunction with the bearing 51, guides the pintle 75 for rotation relative to the supporting bracket 22.

In order to force the pintle 52 into the groove 62, head 61 is constructed with a cam 63. This cam is turned down to form a sloping cam surface 64, best shown in Fig. 3, which engages beneath the pintle 52 and forces the said pintle upwardly 5 into the reduced portion 49 of opening 48 as the keeper is rotated. The outer surface 65 of the cam 63 is arcuate to cause the same to clear the flange 46 of bracket 42, said cam moving in close proximity thereto. The head 61 is also constructed with a stop 66 which is adapted to engage the flange 46 of bracket 22 when the pintle 52 is in engagement with groove 62 to limit further swinging movement of the keeper 57. The bracket 22 is preferably arranged so that the stop 66 is 10 uppermost whereby the keeper is held through the action of gravity in proper position. The body 58 of keeper 57 is provided with two upstanding lugs 67 and 68. These lugs are spaced apart a distance slightly greater than the width of the 20 average screw driver and are used for rotating the keeper 57. When the screw driver is placed between these lugs and turned rotational movement is imparted to keeper 57. The lug 67 is preferably constructed a little longer than the lug 25 68 so that the same may be grasped by a pair of pliers and the device rotated thereby instead of by a screw driver.

My improved sash stay and fastener is adapted to be locked in closed position by the swinging of 30 the two arms 18 and 19 jointly after the sash is in closed position. For this purpose the two arms 18 and 19 are of the same length from pivot to pivot and the pivots formed by pintle 52 and rivet 31 are disposed so that the same overlie one another when the storm sash is closed. In addition, a lug 71 is employed which extends outwardly from the arm 18 and which is adapted to engage the edge 72 of arm 19 when the two arms are brought together. When the arms are swung 40 into final position, this lug resists opening of the sash and holds the same in locked position.

The method of installing and using the invention is as follows. The storm sash 10 is first closed, as shown in Figs. 2 and 3, and the two arms 18 and 19 of the sash folded up and placed along the stop 12 and rail 16. The fasteners may be arranged at any desired locality with reference to the hinge of the sash, it being borne in mind that the lower the disposition of the fastener the less the movement of the sash. While properly disposed the bracket 22 is secured to sash 14 through screws 47. The uppermost of the screws 28 is next applied and thereafter the 50 sash is opened and the lowermost of said screws is next applied. If two sash fasteners are employed, the other is similarly installed, care being taken to install the fasteners with the pivots of the brackets thereof at the same distance from the axes of the hinges of the storm sash. The arms 18 and 19 of the fastener are prevented from fully opening by means of the corner 43 of strap 45 which engages edge 44 of arm 19. By merely manipulating the sash through the 60 pull attached to the lower rail thereof the sash may be opened and closed and the two arms 18 and 19 follow the movement of the sash and swing from open to closed position and vice versa. When the sash has been completely closed the 70 arrangement of the parts is as shown in Figs. 2 and 3. If it becomes desirable to lock the sash, the two arms 18 and 19 are swung jointly from the position shown in Figs. 2 and 3 to that shown in Fig. 4. In the latter position the lug 71 pre- 75

vents opening of the arms and the sash remains locked in closed position.

When, at the end of the season, the storm sash is to be removed, the keeper 57 is swung by means 5 of a pair of pliers or screw driver to disengage the pintle 52 from bearing 51. Thereafter the pintle may be slid outwardly from the opening 48. This is accomplished by pressing the two 10 arms 18 and 19 together. To facilitate such movement, the arm 18 is constructed with an offset 13. Arms 18 and 19 may, if desired be constructed with ribs 74 which stiffen the same. In Fig. 2 the keeper 57 has been shown as swung away from the pintle 52, said pintle being in a 15 position to be disengaged from the bracket 22. A bracket similar to bracket 22 may be applied to the screen sash if a screen sash is to be used in place of the storm sash. The pintle 52 may be thereafter applied to the bracket of the screen 20 sash and the screen sash may then be operated in identically the same manner as the storm sash.

The advantages of my invention are manifest. An extremely simple and practical device is provided whereby storm sash or screen sash may be 25 held in adjusted position in a manner such as to prevent rattling. The device for holding the parts detachably connected is easily operated and will not become unintentionally disengaged. The sash stay and fastener can be constructed at a 30 nominal cost. By means of the locking lug utilized the sash can be locked in closing position.

Changes in the specific form of my invention, as herein disclosed, may be made within the 35 scope of what is claimed without departing from the spirit of my invention.

Having described my invention, what I claim as new and desire to protect by Letters Patent is:

1. A sash fastener comprising a pair of jointed arms, a mounting pivoted to the end of one of 40 said arms, a pintle issuing from the end of the other arm and being constructed with a groove, a bracket having a base and a flange extending therefrom, said flange being formed with an opening adapted to receive said pintle, said opening 45 having a reduced portion forming a bearing for said pintle and receiving said groove, said reduced portion being disposed away from the base of the bracket, a keeper pivoted to the base of said bracket and having a part adapted to extend between said base and pintle for urging said pintle into engagement with said bearing.

2. A sash fastener comprising a pair of jointed arms, a mounting pivoted to the end of one of 55 said arms, a pintle issuing from the end of the other arm and being constructed with a groove, a bracket having a base and a flange extending therefrom, said flange being formed with an opening 60 having a reduced portion forming a bearing for said pintle and receiving said groove, said reduced portion being disposed away from the base, a keeper pivoted to the base of said bracket and having a cam adapted to be moved in between the base and pintle and operating to force 65 the pintle into engagement with said bearing.

3. A sash fastener comprising a pair of jointed arms, a mounting pivoted to the end of one of 70 said arms, a pintle issuing from the end of the other arm and being constructed with a groove, a bracket having a base and a flange extending therefrom, said flange being formed with an opening 75 having a reduced portion forming a bearing for said pintle and receiving said groove, said reduced portion being disposed away from the

base, a keeper pivoted to the base of said bracket and having a cam adapted to be moved in between the base and pintle and operating to force the pintle into engagement with said bearing and a groove in said keeper at the end of said cam and in which said pintle is disposed when the keeper is in operative position.

4. A sash fastener comprising a pair of jointed arms, a mounting pivoted to the end of one of 10 said arms, a pintle issuing from the end of the other arm and being constructed with a groove, a bracket having a base and flange extending therefrom, said flange being formed with an opening 15 adapted to receive said pintle, said opening having a reduced portion forming a bearing for said pintle and receiving said groove, said reduced portion being disposed away from the base, a keeper pivoted to the base of said bracket and having a cam adapted to be moved in between the base and pintle and operating to force the pintle into engagement with said bearing, a groove in 20 said keeper at the end of said cam and in which said pintle is disposed when the keeper is in operative position and a stop on said keeper for engagement with said flange, said stop limiting 25 movement of the keeper when the pintle is in engagement with the groove of the keeper.

5. A sash fastener comprising a pair of jointed arms, a mounting pivoted to the end of one of 30 said arms, a pintle issuing from the end of the other arm and being constructed with a groove, a bracket having a base and a flange extending therefrom, said flange being formed with an opening 35 adapted to receive said pintle, said opening having a reduced portion forming a bearing for said pintle and receiving said groove, said reduced portion being disposed away from the base, a keeper pivoted to the base of said bracket and having a part adapted to extend between said base and pintle for urging said pintle into engagement with said bearing and a pair of spaced lugs issuing 40 outwardly from said keeper and between which a tool may be inserted for the purpose of turning said keeper.

6. A sash fastener comprising a pair of jointed 45 arms, a mounting pivoted to the end of one of said arms, a pintle issuing from the end of the other arm and being constructed with a groove, a bracket having a base and flange extending therefrom, said flange being formed with an opening 50 adapted to receive said pintle, said opening having a reduced portion forming a bearing for said pintle and receiving said groove, said reduced portion being disposed away from the base, a keeper pivoted to the base of said bracket and 55 a cam on said keeper adapted to be moved between said pintle and base for urging said pintle into engagement with said bearing, a stop on said keeper for engagement with said flange for limiting the movement of said keeper, said keeper being constructed with a groove disposed between said cam and stop in which the pintle is received when the keeper is in operative position.

7. A sash fastener comprising a pair of jointed 65 arms, a mounting pivoted to the end of one of said arms, a pintle issuing from the end of the other arm and being constructed with a shoulder, a bracket having a base and flange extending therefrom, said flange being formed with an 70 opening adapted to receive said pintle, said opening having a reduced portion forming a bearing for said pintle and receiving said pintle adjacent said shoulder, said reduced portion being disposed away from the base, a keeper pivoted to the 75

- base of said bracket and a cam on said keeper adapted to be moved between said pintle and base for urging said pintle into engagement with said bearing, a stop on said keeper for engagement with said flange for limiting the movement of said keeper, said keeper being constructed with a groove disposed between said cam and stop in which the pintle is received when the keeper is in operative position.
8. A sash fastener comprising a pair of jointed arms, a mounting pivoted to the end of one of said arms, a pintle issuing from the end of the other arm and being constructed with a shoulder, a bracket having a base and flange extending therefrom, said flange being formed with an opening adapted to receive said pintle, said opening having a reduced portion forming a bearing for said pintle and receiving said pintle adjacent said shoulder, said reduced portion being disposed away from the base, a keeper pivoted to the base of said bracket and a cam on said keeper adapted to be moved between said pintle and base for urging said pintle into engagement with said bearing, said keeper being constructed with a groove following said cam and in which said pintle is received when the keeper is in operative position.
9. A sash fastener comprising a pair of jointed arms, a mounting pivoted to the end of one of said arms, a pintle issuing from the end of the other arm and being constructed with a shoulder, a bracket having a base and flange extending
- therefrom, said flange being formed with an opening adapted to receive said pintle, said opening having a reduced portion forming a bearing for said pintle and receiving said pintle adjacent said shoulder, said reduced portion being disposed away from the base, a keeper pivoted to the base of said bracket and having a part adapted to extend between said base and pintle and arranged in parallel relation with the axis of said pintle, said part having a longitudinally extending groove adapted to engage the pintle outwardly of said shoulder to urge the pintle into engagement with said bearing, said groove holding the keeper from disengagement from said pintle.
10. A sash fastener comprising a pair of jointed arms, a mounting pivoted to the end of one of said arms, a pintle issuing from the end of the other arm and being constructed with a shoulder, a bracket having a base and flange extending therefrom, said flange being formed with an opening adapted to receive said pintle, said opening having a reduced portion forming a bearing for said pintle and receiving said pintle adjacent said shoulder, said reduced portion being disposed away from the base, a keeper pivoted to the base of said bracket, the axis of the pivot of said keeper being at right angles to the axis of said pintle, said keeper having a part adapted to extend between said base and pintle and urging said pintle into engagement with said bearing.

CHESTER O. GOSERUD.
